Primary Examiner — Anhdao Doan*Assistant Examiner* — John R Yeh(74) *Attorney, Agent, or Firm* — James E. Howard; Andre Pallapies(57) **CLAIM**

The ornamental design for a dishwasher bar handle, as shown and described.

DESCRIPTION

FIG. 1 is a front perspective view of a dishwasher bar handle showing my new ornamental design;

FIG. 2 is a top view thereof;

FIG. 3 is a front view thereof;

FIG. 4 is a rear view thereof; and,

FIG. 5 is a right side view thereof, with the left side view being a mirror image thereof.

The broken lines in FIG. 4 are included for the purpose of illustrating portions of the dishwasher bar handle that form no part of the claimed design.
